(57) **CLAIM**

The ornamental design for wireless earbuds, as shown and described.

DESCRIPTION

FIG. 1 is a rear perspective view of the right earbud of wireless earbuds showing the new design, shown separately to show aspects of the design that are not visible when combined;

FIG. 2 is a front perspective view of the right earbud of the wireless earbuds shown in FIG. 1;

FIG. 3 is a right side view of the right earbud of the wireless earbuds shown in FIG. 1;

FIG. 4 is a left side view of the right earbud of the wireless earbuds shown in FIG. 1;

FIG. 5 is a top view of the right earbud of the wireless earbuds shown in FIG. 1;

FIG. 6 is a bottom view of the right earbud of the wireless earbuds shown in FIG. 1;

FIG. 7 is a front view of the right earbud of the wireless earbuds shown in FIG. 1;

FIG. 8 is a rear view of the right earbud of the wireless earbuds shown in FIG. 1;

FIG. 9 is a rear perspective view of the left earbud of the wireless earbuds, shown separately to show aspects of the design that are not visible when combined;

FIG. 10 is a front perspective view of the left earbud of the wireless earbuds shown in FIG. 9;

FIG. 11 is a left side view of the left earbud of the wireless earbuds shown in FIG. 9;

FIG. 12 is a right side view of the left earbud of the wireless earbuds shown in FIG. 9;

FIG. 13 is a top view of the left earbud of the wireless earbuds shown in FIG. 9;

FIG. 14 is a bottom view of the left earbud of the wireless earbuds shown in FIG. 9;

FIG. 15 is a front view of the left earbud of the wireless earbuds shown in FIG. 9; and,

(Continued)

FIG. 16 is a rear view of the left earbud of the wireless earbuds shown in FIG. 9.
